(57) **CLAIM**

The ornamental design for a pool coping, as shown and described.

DESCRIPTION

FIG. 1 is a perspective view of a pool coping, showing the new design;

FIG. 2 is a front elevational view thereof;

FIG. 3 is a rear elevational view thereof;

FIG. 4 is a right-side elevational view thereof, the left-side elevational view being a mirror image thereof;

FIG. 5 is a top plan view thereof; and,

FIG. 6 is a bottom plan view thereof.

The broken lines in FIGS. 1-3, 5 and 6 are included to indicate indeterminate width.
